(57) CLAIM

The ornamental design for a prey marker, as shown and described.

DESCRIPTION

FIG. 1 is a front perspective view of a first embodiment of the prey marker;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof;

FIG. 7 is a bottom plan view thereof;

FIG. 8 is a front perspective view, wherein the tail portion is hatched to indicate that it is colored orange;

FIG. 9 is a front and left side perspective view of a second embodiment of the prey marker;

FIG. 10 is a rear and right side view thereof, with the other views of the second embodiment being the same as those in FIGS. 2-7 described above, except with the alternative coupling of the tail portion to the head portion being present;

FIG. 11 is a front and left side perspective view of a third embodiment of the prey marker; and,

FIG. 12 is a rear and right side view thereof, with the other views of the third embodiment being the same as those in FIGS. 2-7 described above, except with the alternative coupling of the tail portion to the head portion being present.

The prey marker is shown broken away to indicate indeterminate length.

It should be understood that the labels used herein for describing orientation (e.g., front, back, top, bottom, right, and left) are merely for reference, and the embodiments of my design may be disposed in any manner and still be within the scope of the present invention.
